US00D620677S

(12) **United States Design Patent**
Rea et al.

(10) **Patent No.:** US D620,677 S
(45) **Date of Patent:** ** Aug. 3, 2010

(54) **SINGLE-LOBE BAG FOR INFUSION
PRODUCTS**

(75) Inventors: **Dario Rea**, Monterenzio (IT); **Sauro Rivola**, Riolo Terme (IT)

(73) Assignee: **I.M.A. Industria Macchine Automatiche S.p.A.**, Bologna (IT)

(**) Term: **14 Years**

(21) Appl. No.: **29/271,902**

(22) Filed: **Jan. 30, 2007**

(30) **Foreign Application Priority Data**

Jul. 31, 2006 (IT) BO2006O0046

(51) **LOC (9) Cl.** 01-01

(52) **U.S. Cl.** D1/199

(58) **Field of Classification Search** D1/102,
D1/105, 199; D9/703; 426/79, 83, 394;
99/279; 206/0.5

See application file for complete search history.

(57) **CLAIM**

The ornamental design for single-lobe bag for infusion products, as shown and described.

DESCRIPTION

FIG. 1 illustrates a first single-lobe bag in perspective view;

FIG. 2 illustrates a first single-lobe bag in front face view;
FIG. 3 illustrates a first single-lobe bag in right-hand side view;

FIG. 4 illustrates a first single-lobe bag in rear face view;
FIG. 5 illustrates a first single-lobe bag in left-hand side view;

FIG. 6 illustrates a first single-lobe bag in bottom plan view;
FIG. 7 illustrates a second single-lobe bag in perspective view;

FIG. 8 illustrates a second single-lobe bag in front face view;
FIG. 9 illustrates a second single-lobe bag in right-hand side view;

FIG. 10 illustrates a second single-lobe bag in rear face view;
FIG. 11 illustrates a second single-lobe bag in left-hand side view;

FIG. 12 illustrates a second single-lobe bag in bottom plan view;

FIG. 13 illustrates a third single-lobe bag in perspective view;
FIG. 14 illustrates a third single-lobe bag in front face view;

FIG. 15 illustrates a third single-lobe bag in side view;

FIG. 16 illustrates a third single-lobe bag in rear face view;

FIG. 17 illustrates a third single-lobe bag in bottom plan view;

FIG. 18 illustrates a fourth single-lobe bag in perspective view;

FIG. 19 illustrates a fourth single-lobe bag in front face view;

FIG. 20 illustrates a fourth single-lobe bag in side view;

FIG. 21 illustrates a fourth single-lobe bag in rear face view;

FIG. 22 illustrates a fourth single-lobe bag in bottom plan view;

FIG. 23 illustrates a fifth single-lobe bag in perspective view;

FIG. 24 illustrates a fifth single-lobe bag in front face view;

FIG. 25 illustrates a fifth single-lobe bag in side view;

FIG. 26 illustrates a fifth single-lobe bag in rear face view;

and,
FIG. 27 illustrates a fifth single-lobe bag in bottom plan view.
